RIBBON-VIBRATING MECHANISM.

949,818.

Specification of Letters Patent. Patented Feb. 22, 1910.

Application filed October 6, 1909. Serial No. 521,293.

To all whom it may concern:

Be it known that I, THEODOR EUGEN BUSCHMANN, mechanical engineer, a subject of the Emperor of Germany, residing at Chemnitz, Germany, have invented new and useful Improvements in Ribbon-Vibrating Mechanism, of which the following is a specification.

The invention relates to improved mechanism for actuating the ink-ribbon fork of typewriters, of the kind in which the fork that lifts the ribbon in front of the printing point can be raised into two different positions as desired, namely in such a manner that after being raised either to its highest or to its intermediate position the fork returns to its position of rest thus allowing the letter last printed to become visible.

By means of such an arrangement either a narrow single-colored ribbon, or a bicolored ribbon of double width or two narrow ribbons of different colors can be used.

The subject of the invention is distinguished from known devices having this object, by simplicity of constructions which insures a reliable method of operation inasmuch as in the improved mechanism it is impossible for instance for the ribbon to be raised so high by the ink-ribbon fork if the keys are struck somewhat hard, as to print a letter partly in one color and partly in the other. The changing from one color to the other is effected by pressing one and the same key, and this change is at the same time visibly indicated to the typist by a pointer moving over two differently colored strips.

In the accompanying drawings which show only those parts of a typewriter that are necessary for the understanding of the invention--Figure 1 is vertical longitudinal section of a typewriter embodying the present improvements. Fig. 2 illustrates the differently colored strips on the cover-plate of the machine with a pointer for indicating to the typist which ribbon is in use. Fig. 3 is a plan of an important detail included in Fig. 1. Fig. 4 is a view of the changing shaft as seen from the front of the machine. Fig. 5 is a view of a detail included in Fig. 4. Fig. 6 illustrates the ink-ribbon fork with the upper half of the ribbon in position for writing. Fig. 7 shows the ink-ribbon fork with the lower half of the ribbon in position

for writing; Figs. 8, 9 and 10 illustrate by way of example one construction of the changing mechanism by means of which the changing shaft is alternately rotated into its two end positions. Figs. 11, 12 and 13 illustrate by way of example another construction of the changing mechanism.

In order to facilitate the understanding of the improved mechanism and its method of operation, the known parts of the machine illustrated in the drawings will first be described.

The type bars 1 rock on a common axle 2 in the form of a circular arc. The key levers (not shown in Fig. 1) operate the type bars in the usual manner, they rest on the universal bar 3 situated in the lower part of the frame of the machine, and compel the universal bar to rock downward on the axle 4 each time a key is struck. Each downward movement is transmitted by the arm 5 through the medium of a pin 6 projecting laterally, to an angle lever 8, 9, connected rigidly together and pivoting on the axle 7. The arm 9 communicates by means of a rod 10 with the lever 12 pivoted on the fixed axle 11 to the free end of which is pivoted the ink-ribbon fork 13 carrying the two ink-ribbons 14 and 15 at its upper end. When therefore a key lever is depressed, the arm 9 rocks through a small angle in the direction of the arrow in Fig. 1 and lifts the ink-ribbon fork 13 so that the ribbon reaches a position in front of the writing point.

In order that the parts 8, 9, 10, 12, 13 may not be jerked to-and-fro too violently when typing quickly, the pin 6 which transmits the motion of the arm 5 of the universal bar to the arms 8, 9 only rests on the arm 8, and contact is secured by the lever 16 which is pivoted freely to the arm 8 and held in its end position by means of a spring 17. This spring 17 is so weak that on rapidly repeated striking of the keys, the universal bar 3 and its arm 5 perform their full movement each time together with the pin 6. The parts 8, 9, 10, 12 and 13 however, which are actuated by the pin 6, are not obliged to follow. The jaw formed by the arm 8 and the lever 16 opens a small amount when the pin 6 again moves upward and closes again at once on immediately afterward depressing the universal bar 3. As soon as the typist writes more slowly or makes a small

pause the spring 17 has time enough to close the jaw (8, 16) and to pull the arm 8 upward.

The above-described mechanism is supplemented according to the present invention, by the following arrangements. A straight lever 18, 19 is arranged on the pin 6 at the end of the arm 5 of the universal bar, in such a manner that it is carried at two points by the pin 6 and the strip of metal 20 (Fig. 3) connecting the two bearings passes over the arm 5 and over the jaw side of the lever 16. A pin 21 projects laterally from the lever arm 18 and a pin 22 upon which rests the lower edge of the lever arm 19 is attached to the arm 8.

A shaft 23 (Fig. 4) is pivoted on centering screws situated in the side-plates of the machine. To this changing shaft 23 are rigidly fixed the following parts. Close to the left hand side-plate is mounted the hooked rocking member 24, 25, 26, 27, which as will be hereinafter described, is alternately rotated into its opposite extreme positions by each movement of a bell-crank lever 28, 29 by means of pins 30, 31 projecting laterally from the same. The movement of the bell-crank lever 28, 29 is produced by means of a key lever 32, 33. Farther to the right on the changing shaft is mounted a long arm 34 whose pin 35 engages in the slot 36 of the indicator rod 37. The pointer 38 of the rod 37 projects through the front plate of the machine and can be made to rise or fall between two indicating strips 39, 40 of different colors (Fig. 2). Near the middle of the shaft 23 is attached a two-armed member 41, 42. The lower arm 42 of the latter forms a hook. The end of the upper arm 41 is bent at right angles to itself. The pin 21 of the lever 18, 19 is located in the rocking plane of the hooked arm 42 and the upper bent portion of the arm 41 can strike a projection 43 adjustably mounted on the rod 10. To the right-hand end of the shaft 23 is attached a V-shaped arm 44 carrying a roller 47, having a cross-piece provided at its free end with two adjusting screws 45, 46 (Fig. 5), by means of which the extreme positions of rotation of the shaft 23 can be regulated. On each rotation of the shaft 23, the roller 47 jumps under the V-shaped bent end of the locating spring 48 and secures the shaft 23 spindle in its new position.

The method of operation of the above described devices is as follows, with reference to Figs. 6 and 7. Fig. 6 illustrates that position of the mechanism actuating the ink-ribbon fork, in which the latter is raised and the upper half of the ribbon is in use. The shaft 23 is in the position indicated in Fig. 1. The pointer 38 stands at the upper colored strip 39 and the hooked arm 42 is in a position beyond the range of movement

of the pin 21 on the lever arm 18. If the universal bar 3 be depressed, the pin 6 drives the arms 8, 9 in the direction of the arrows shown in Figs. 1 and 6 and the ink-ribbon fork 13 is lifted only as high as if the new device was not present at all. Its presence can however be noticed, since, while formerly the ribbon often jumped higher than was necessary, the projection 43 adjustably mounted on the rod 10 now strikes the arm 41 and thus limits the highest position of the ribbon 14. If the lower ribbon 13 is now to be used, the shaft 23 is turned to the left through a small angle by depressing the key lever 33 whose arm 32 actuates the bell-crank lever 28, 29 and the pin 31 attached to its arm 29 engages in the hook 24 of the hooked member 24, 25, 26, 27 and turns the shaft 23 together with all the parts attached to the same, into the position indicated in Fig. 7. The arm 34 actuating the indicator rod 37 is hereby lowered together with the rod 37 and the pointer 38 now stands at the lower colored strip 40. The projection as well as the hooked arm 41, 42 have also been rotated, so that the arm 41 moves away from the projection 43 and the hooked arm 42 moves into the range of the pin 21 on the lever 18. If on depressing a key the universal bar 3 now moves downward and with it the arm 6 and its pin 6, the two-armed lever 18, 19 cannot swing downward like a member attached to the arms 8, 9 as shown in Fig. 6, but must now be equivalent to a member rigidly attached to the universal bar 3, because the hook of the arm 42 holds back the lever arm 18 by means of its pin 21. The effective length of the arm 5 of the universal bar is thereby increased by almost the entire length of the lever arm 19, and since the latter rests on the pin 22 the effective length of the arm 3 is simultaneously decreased by the distance between the two pins 6 and 22. Since, however, the angular movement of the arm 5 of the universal bar remains the same, the consequence of this alteration in the lengths of the levers is an increased angular movement of the arms 8, 9 and a correspondingly increased displacement of the ink-ribbon fork 13. In the case also of this increased displacement the arm 41 forms a stop for the projection 43 of the rod 10 when the keys are struck too hard. If on the contrary the keys are struck too feebly or not uniformly, the ink-ribbon fork 13 is always lifted high enough before the type reaches the paper, since the lifting of the ink-ribbon fork with the ribbons always takes place positively. The return only of the ink-ribbon fork is dependent on the speed of typing since it is effected by means of the spring 17.

The changing mechanism illustrated in Figs. 8, 9, 10 will now be described. In Figs. 1 to 7 the parts of this device have re-

ceived the reference numbers 24 to 33. In Figs. 8 to 10 the key lever 32, 33 has been omitted, as the movement of the bell-crank lever 28, 29 which effects the change of ribbons can be performed in various ways. The locating lever 44 however, which, in Figs. 1 to 7 is shown mounted on the changing shaft 23 separately from the changing mechanism is in this case rigidly connected to the latter. The fixing roller 47 is mounted on the end of the arm 44 and the V-shaped bent end of the retaining spring 48 rests on the roller 47.

The improved device thus comprises a hooked member formed of two hooks 24, 25 and two guiding projections 26, 27 rigidly attached to the shaft 23. The pivot 49 of a bell-crank lever 28, 29 is arranged vertically under the center line of the shaft 23 and is movable in the direction of the arrows in Figs. 8 to 10. Pins 30, 31 project respectively from the ends of the bell-crank lever arms into the plane of the hooked member 24 to 27.

The operation is as follows: In consequence of the position of unstable equilibrium of the bell-crank lever 28, 29, when it is lifted vertically from the position shown in Fig. 8 the pin 30 on the lever arm 18 must slide along the outer edge of the guiding projection 27, because its center of gravity is displaced to the right of its pivot. When the pin 30 strikes the hook 25 the hooked member must turn in a clockwise direction during the remainder of the movement, and the roller 47 passes below the dead point of the spring 48. This position is indicated in Fig. 9. If the bell-crank lever 28, 29 be now lowered, the pin 30 again slides along the outer edge of the guiding projection 27 and since it is now displaced much farther to the left, the bell-crank lever 28, 29 is now turned over in this direction and its center of gravity displaced to the left of its axis of rotation 49. Fig. 10 illustrates this position of the bell-crank lever 28, 29 and shows at the same time that on the next movement of the latter the pin 31 will strike the hook 24 and turn the hooked member and the shaft 23 again into the position shown in Fig. 8.

Another construction of the changing mechanism is illustrated in Figs. 11, 12, 13. This differs from the one previously described merely by the arrangement at the center of gravity of the bell-crank lever 28, 29 instead of being shifted by two guiding projections on the hooked member 24, 25, 26, 27 is shifted in this case by means of a pin 51 projecting laterally from a third projection 50. This pin 51 reaches into a trapezium-shaped opening between the arms 28, 29 of the bell-crank lever. This opening terminates in an open guiding slot into which the pin 51 projects when the bell-

crank lever 28, 29 is in its lowest position (see Figs. 11 and 13). When the hooked member is turned over toward the right, the center of gravity of the bell-crank lever 28, 29 lies to the left of its pivot 49. When the bell-crank lever is moved upward, the pin 51 is placed against the lateral edge of the hook 24 and is securely guided into the latter.

The principal advantage of the improved mechanism over other known arrangements is that it comprises neither springs liable to break nor delicate guiding parts, while complete certainty of working is secured by causing the correct pin to be moved into the corresponding hook by means of the force produced by shifting the center of gravity.

Having now particularly described and ascertained the nature of my said invention and in what manner the same is to be performed I declare that what I claim is:

1. In a typewriting machine, the combination, with the frame, an arm carrying a universal bar, mounted to rock therein, an angle lever mounted to rock in said frame, an ink-ribbon fork actuating rod connected with said angle lever, a pin on said arm of the universal bar resting on said angle lever, and a spring-pressed lever pivoted on, and pressing said pin against said angle lever, of a two-armed lever pivoted on said arm of the universal bar, one arm of the latter lever extending beyond said arm of the universal bar and adapted to coact with said angle lever and means for holding the other arm of said two-armed lever stationary whereby the operative length of said arm of the universal bar is increased.

2. In a typewriting machine, the combination, with the frame, an arm carrying a universal bar, mounted to rock therein, an angle lever mounted to rock in said frame, an ink-ribbon fork actuating rod connected with said angle lever, a pin on said arm of the universal bar resting on said angle lever, and a spring-pressed lever pivoted on, and pressing said pin against said angle lever, of a two-armed lever pivoted on said arm of the universal bar, one arm of the latter lever extending beyond said arm of the universal bar and adapted to coact with said angle lever, lever-operated changing mechanism for holding the other arm of said two-armed lever stationary whereby the operative length of said arm of the universal bar is increased, and means connected with said changing mechanism for limiting the movement of said rod.

3. In a typewriting machine, the combination, with the frame, an arm carrying a universal bar, mounted to rock therein, an angle lever mounted to rock in said frame, an ink-ribbon fork actuating rod connected with said angle lever, a pin on said arm of the universal bar resting on said angle lever,

and a spring-pressed lever pivoted on, and pressing said pin against said angle lever, of a two-armed lever pivoted on said arm of the universal bar, one arm of the latter lever 5 extending beyond said arm of the universal bar and adapted to coact with said angle lever, lever-operated changing mechanism for holding the other arm of said two-armed lever stationary whereby the operative length 10 of said arm of the universal bar is increased, means connected with said changing mechanism for limiting the movement of said rod, and ribbon indicating means operatively-connected with said changing mechanism.

4. In a typewriting machine, the combination, with the frame, an arm carrying a universal bar, mounted to rock therein, an angle lever mounted to rock in said frame, 20 an ink-ribbon fork actuating rod connected with said angle lever, a pin on said arm of the universal bar resting on said angle lever, and a spring-pressed lever pivoted on, and pressing said pin against said angle lever, of 25 a two-armed lever pivoted on said arm of the universal bar, one arm of the latter lever extending beyond said arm of the universal bar and adapted to coact with said angle lever, a rock shaft carrying a rocking member having 30 hooks, mounted in said frame, a ribbon indi-

cator slideable on said frame means for operating the same from the rock shaft, a two-armed member fixed on said rock shaft, one arm of said member having a hook adapted to hold stationary the second arm of said two-armed lever, a stop adjustable on said inked ribbon fork actuating rod, the other arm of said member limiting the movement of said stop, a key lever mounted to rock in said frame, and a bell-crank lever arranged in 35 unstable equilibrium under the axis of rotation of said rocking member and having pins adapted to engage in the hooks of the same.

5. In a typewriting machine, the combination, with the frame and a key lever pivotally mounted therein, of a rock shaft mounted in the frame, a rocking member having arms fixed on said shaft, and a bell-crank lever having pins on its arms pivotally mounted in unstable equilibrium under 40 the axis of rotation of said rocking member, said pins normally resting against said arms. In testimony whereof I have signed my name to this specification in the presence of two subscribing witnesses.
